DISPLAY CARTON FOR A CHILD'S WEARING APPAREL OR THE LIKE

Victor Shalom, 236 5th Ave., New York, N.Y.

Filed Mar. 17, 1959, Ser. No. 55,028

Term of patent 14 years

(Cl. D58—12)

FIG. 2

Fig. 1 is a front perspective view of a display carton for a child's wearing apparel or the like, showing my new design; and

Fig. 2 is a rear elevational view thereof.

The side not shown is the same as the side shown.

I claim:

The ornamental design for a display carton for a child's wearing apparel or the like, as shown and described.
